(57) **CLAIM**

The ornamental design for a rotary dicing machine as shown and described.

DESCRIPTION

FIG. 1 is an exploded perspective view of a rotary dicing machine showing our new design, where a first component, a second component, and a third component are shown separately from ease of illustration;

FIG. 2 is another exploded perspective view thereof;

FIG. 3 is an exploded front elevational view thereof;

FIG. 4 is an exploded rear elevational view thereof;

FIG. 5 is an exploded left side elevational view thereof;

FIG. 6 is an exploded right side elevational view thereof;

FIG. 7 is a top plan view thereof;

FIG. 8 is a bottom plan view thereof;

FIG. 9 is an exploded perspective view of the rotary dicing machine where the first component is assembled with the second component;

FIG. 10 is a perspective view of the rotary dicing machine;

FIG. 11 is an enlarged view of portion 11 shown in FIG. 1;

FIG. 12 is an enlarged view of portion 12 shown in FIG. 2; and,

FIG. 13 is an enlarged view of portion 13 shown in FIG. 2. The dash-dot broken lines in the drawings depict portions of the rotary dicing machine that form no part of the claimed design. The dot-dot broken lines in FIGS. 1, 2, and 11-13 represent boundaries of the enlarged portions and form no part of the claimed design.
